STATION INDICATOR

Filed July 7, 1927

Ernest
Christ Dunn

UNITED STATES PATENT OFFICE.

CHRIST DUNN, OF MILWAUKEE, WISCONSIN.

STATION INDICATOR.

Application filed July 7, 1927. Serial No. 204,073.

This invention relates to station indicators.

Objects of this invention are to provide a novel form of station indicator which 5 may be used with street cars, for instance, to indicate the station the car is approaching, and which is so constructed that it is semi-automatic in its action and controlled by the motorman by means of a manually 10 operable switch, so that the actuation of the indicator is initiated by the motorman and is arrested in an automatic manner.

Further objects are to provide a simple 15 type of motor driven indicator which is readily controlled from a remote point, and which is provided with an indicator adjacent the remote point of control to show the condition of the motor circuit.

Further objects are to provide a simple 20 type of reverse winding mechanism which may be readily operated to rewind the indicating strip.

An embodiment of the invention is shown 25 in the accompanying drawings in which:

Figure 1 is a sectional view of the device, 30 such view being taken on the line 1-1 of Figure 2;

Figure 2 is a sectional view on the line 35 2-2 of Figure 1;

Figure 3 is a schematic view showing the 40 wiring circuits.

Referring to the drawings, it will be seen 45 that the indicator comprises a casing 1 which may be attached within the car, preferably adjacent the front end within full view of all the occupants. This casing is provided with a window 2 in its front through which the successive displayed legends may appear. The legends 3 are formed upon a strip 4 which is carried by a lower drum 5 and an upper drum 6. The lower drum is loose upon the shaft 7 and the upper drum is either loose or fast upon the shaft 8. The drums are provided with clutch members 9 and 10, respectively, which are rigid therewith and are adapted to cooperate with similar clutch members 11 and 12. The clutch members 11 and 12 are provided with grooves within which projections carried 50 by the forked end of a lever 13 fit. This lever is pivoted, as indicated at 14, intermediate its ends and is urged by means of the spring 15 into the position shown in Figure 1. The clutch member 11 is slidably splined 55 upon the shaft 7, and it is to be noted that the shaft 7 is provided with a worm wheel

16 cooperating with a worm 17 formed on the shaft of a small electric motor 18.

The clutch member 12 is rigid with a sleeve 19 which in turn is rigid with a crank 20. When it is desired to reverse the winding of the strip, that is to say, to rewind and set the device in its initial condition, all that is necessary is to press the crank 20 inwardly and rotate it. The inward motion 60 of the crank couples the clutch members 10 and 12 so that the upper clutch is closed. The lower clutch is open due to the action of the lever 13, as is obvious from an inspection of Figure 1. The rewinding may be 65 readily effected by merely rotating the crank while it is held inwardly. After rewinding, the crank is merely released, the spring 15 throwing the parts into the position shown in Figure 1.

It is to be noted that one face of the drum 5 carries a projecting pin 21 (see Figures 1 and 3) which contacts with an insulated portion 22 of a lever 23. This portion 22 is also cam shaped, as shown in Figure 3, and the upper end of the lever carries a movable contact member 24. A stationary contact 25 is placed in the path of movement of the contact 24. A spring 26 is provided for urging the lever 23 towards contact closing 70 position. The direction of rotation of the drum 5 is indicated in Figure 1.

Adjacent the controller, or in any place 75 within easy access of the motorman, a switch 27 is positioned and is connected to one of the supply mains 28. The other side of the switch is connected by means of the conductor 29 to a small lamp 30 positioned adjacent the motorman. From this lamp, a conductor 31 extends to the motor 18. A 80 return conductor 32 extends from the other side of the motor to the other supply main 33. It is to be noted that the contact 25 is connected to the main 28 by means of the conductor 24 and that the other contact 24 85 is connected by means of the conductor 35 to the conductor 29. The purpose of this arrangement will immediately appear.

Assume that the car approaching a station and the motorman desires to change the 90 sign. All that is necessary is to temporarily close the switch 27 and current will flow through the lamp 30 and through the motor 18. It is not necessary to hold the switch closed until the desired sign appears and 95 the motorman may immediately release the switch after initiating the operation of the 100

110

device. It is to be noted that after a very brief interval the pin 21 rides clear of the cam portion 22 of the lever and allows the contacts to close, thus forming a bridge circuit around the switch 27 and allowing the motor to continue to operate. When the motor has rotated the drum one turn, the pin 21 strikes the arm 22 and opens the contacts and thus arrests further motion 10 of the device. It is to be noted also that the cam portion 22 of the spring urged lever acts as a break to arrest the motion of the drum and aid in the quick stopping of the apparatus at the desired point.

15 It is to be noted also that although the wound portions of the strip may vary the effective diameters so that a slight difference in length of travel of the strip is produced for different numbers of turns of the drum, 20 that this may be readily taken care of by properly spacing the insignia 3 along the sheet 4.

It is to be noted that the spring 26 is not of sufficient strength to prevent the movement of the pin past the cam portion 22 of 25 the lever when the device is actuated by the motor, but is sufficient to offer a frictional resistance to overrunning of the drum when the motor circuit is automatically open 30 thereby securing a quick stopping of the apparatus at the exact point desired.

Rewinding of the apparatus is easily accomplished as previously described by merely pressing the crank 20 inwardly and 35 rotating it.

It is to be noted also that the lamp 30 apprises the motorman of the condition of the motor circuit so that he may know at a glance whether the motor is supplied with energy 40 or not.

It will be seen therefore that a very simple type of station indicator has been provided, which is of eminently practical construction and which may be readily produced and easily operated.

Further, it is to be noted that the device has relatively few parts and is free from delicate and easily destroyed mechanisms.

Although the invention has been described in considerable detail, such description is intended as illustrative rather than limiting as the invention may be variously embodied and as the scope of such invention is to be determined as claimed.

I claim:

A station indicating device comprising a casing provided with a window, a motor carried within said casing and having a shaft, a pair of drums mounted within said casing, a pair of shafts loosely carrying said drums and spaced apart, reduction mechanism connecting said motor shaft with one of said shafts, a clutch member slidably splined upon the shaft connected to said reduction mechanism, a sleeve slidable upon the other shaft and having a clutch member thereon, a crank connected to said sleeve, a lever pivoted intermediate its ends and connected at its ends to said clutch members, said drums each having clutch members cooperating with said first mentioned clutch members, and an insignia carrying tape wound upon said drums and adapted to pass said windows.

In testimony that I claim the foregoing I have hereunto set my hand at Milwaukee, in the county of Milwaukee and State of Wisconsin.

CHRIST DUNN.
